UNITED STATES PATENT OFFICE.

GIUSEPPE SINDONI, OF BROOKLYN, NEW YORK.

WINDOW.

1,278,394.

Specification of Letters Patent. Patented Sept. 10, 1918.

Application filed May 10, 1917. Serial No. 167,755.

To all whom it may concern:

Be it known that I, GIUSEPPE SINDONI, a citizen of the United States, residing at Brooklyn, in the county of Kings and State 5 of New York, have invented certain new and useful Improvements in Windows; and I do declare the following to be a full, clear, and exact description of the invention, such as will enable others skilled in the art to 10 which it appertains to make and use the same.

The primary object of the invention is to provide a new and improved type of window, whereby the sash may be swung horizontally, and slid transversely so that when 15 the window is opened the sashes will not project into the room, and be in the way.

Another object of this invention is to provide a window of this character, which 20 is provided with horizontally swinging and transversely sliding sashes, and which sashes have shutters that are also adapted to swing horizontally and to be slid transversely through said sashes so as not to project into the room beyond the sill of the window frame.

In the accompanying drawings:

Figure 1 is an end side elevation showing parts of the sash and shutter broken away 30 and in section;

Fig. 2 is a horizontal section;

Fig. 3 is a vertical section taken on the line 3—3 of Fig. 1;

Fig. 4 is a vertical section taken on the line 4—4 of Fig. 1;

Fig. 5 is a section taken in dotted lines on the line 5—5 of Fig. 2;

Fig. 6 is a bottom plan view of the sash and shutter showing the slots and plates on 40 the same.

In describing my invention I shall refer to the drawings in which similar reference characters designate corresponding parts throughout the several views, and in which 45 the numeral 1 designates the window frame which may be of the ordinary conventional type and which is provided with a top portion 2, a bottom portion 3 which forms a sill, and sides 4.

50 The window frame 1 has mounted therein a pair of sashes 5 which are of the conventional type, being substantially rectangular in shape to form a frame and in which may be disposed panes of glass 6. 55 These sashes 5 when disposed across and within the window frame entirely fill the

same and they may be secured together by any desired type of fastening means at their contacting edges. The sashes 5 are so mounted within the frame 1 that they are 60 adapted to swing horizontally, and slide transversely across the same, and said sashes are of such a width that when they are slid transversely approximately half their length across the frame, as clearly 65 shown in Fig. 2 of the drawings, they will not project from the sill into the room and hence will be out of the way. The pivotal and slidable connections between the sashes and the frame comprise two connecting 70 members 7 for each sash which are disposed between the top of the sashes adjacent their outer edge and the lower edge of the upper portion 2 of the frame, and the bottom of the sashes also adjacent their outer edges, 75 and the top of the sill or bottom portion 3 of the frame. These connections 7 are substantially similar at all four points and for the sake of brevity I will specifically describe only one of the same.

80 The connecting member 7 comprises a vertical pivot pin 8 that has its outer extremity 9 projecting beyond the edge of the portion of the frame to which it is secured, and the same is adapted to be disposed in a 85 longitudinally extending slot 10 in the adjacent edge of the sash 5. This slot 10 extends from the outer edge of the sash to a point approximately midway between its ends and the same is protected by a metallic 90 strip 11 having a longitudinally extending slot 12 therein which aligns with the slot 10. Passing through the vertical pivot 8 is a bearing pin or journal 13, which projects therefrom at either side and has 95 mounted on its projecting end portions, rollers 14. These rollers 14 are normally disposed transversely across the frame 1 for a purpose to be hereinafter more fully described.

100 From the above specific description of the connections 7 between the sashes and the frame, it will be obvious that when the parts of this frame are assembled as shown in Fig. 1 of the drawings, the projecting extremities 105 9 of the pivots 8 will be disposed within the slots 10 in the sashes, and at a point adjacent the outer edges or ends of said sashes. When it is desired to open the sashes for any purpose, they may be swung horizontally, 110 owing to the fact that the same will swing easily on the vertical pivots 8. When swung

outwardly to the position shown in dotted lines in Fig. 2 of the drawings, it will be obvious that one of the edges of such sashes will project past the sill of the window frame out into the room. To remove this obstruction, the sashes are adapted to be slid transversely through the frame for approximately half their length, whereby their projecting ends will be disposed within the outer edge of the sill. This transverse sliding movement is brought about by the fact that the rollers 14 are disposed into contact with the metal strip 11 which forms a track for the same, and owing to the fact that the vertical pivot 8 will form a guide, these sashes may be pushed straight through the frame to the position shown in dotted lines in Fig. 2 of the drawings. The transverse sliding movement of the sashes through the frame is limited owing to the fact that the slots 10 extend approximately only half the width of the sashes, thereby limiting their movement.

The sashes 5 are also provided with protective blinds or shutters 15 which are of substantially rectangular shape and are slightly larger than the glass within said sashes so that when in position they will form a cover for the same. These shutters 15 are connected with the sashes 5, at the inner sides of the same and are adapted to swing horizontally with respect to the same, and the sashes 5 are provided with vertical slots 16 therein adjacent one of their edges, and disposed contiguous to one of the edges of the shutters 15 so that the shutters are also adapted to slide transversely through the slots in said sashes, for approximately half their length so that they also will not project into the room when swung into open position. The connections between the sashes 5 and the shutters 15 are designated by the numeral 17 and they are disposed on the inner sides of said sashes adjacent one of their edges and connect the same with the upper and lower edges of said shutters. These connections 17 are substantially alike in general outline and are four in number and for the sake of brevity I will specifically describe only one of them.

The connection 17 comprises a right angular bracket 18 having one of its arms 19 secured by a screw 20 adjacent the edge of the sash in vertical alinement and contiguous to one end of the slot 16. The other arm 21 of the bracket projects outwardly from the sash at right angles to the same and is disposed across the bottom of the slot. Projecting from the arm 21 is a vertical pivot 22 which has its extremity 23 positioned over said slot and has passing through the pivot adjacent its inner end a bearing pin 24 upon the projecting ends of which are mounted rollers 25.

Within the adjacent edge of the shutter

15 is a longitudinally extending slot 26 and said edge is provided with a metallic strip 27 having therein a longitudinally extending slot 28 alining with the slot 26 in said edge. The slot 26 in the edge of the shutter extends approximately half the length of the same for a purpose to be hereinafter more fully described.

From the above specific description of the connection 17 between the shutters and sashes, it will be obvious that owing to the fact that two of these connections are employed at the top and bottom of each of the shutters and adjacent one of the edges, said shutters are adapted to swing horizontally on the vertical pivots 22 between which they are mounted, from the closed position shown in Fig. 1 of the drawings outwardly. When swung outwardly, it will be obvious that their outer ends will project beyond the sill 3 but when in this position they will be disposed in a single plane with the slot 16 through the sash 5, so that upon pushing the shutters transversely through the frame the same will be projected through the slot 16 for approximately half their length, whereby their projecting ends will be moved past the sill 3 of the frame. The sliding movement of the shutters will be limited owing to the fact that the slot 26 limits the transverse movement of the same, owing to the fact that it only extends across half of their width. When moved transversely, the rollers 25 will slide upon the metal strips 27 which will form a track for the same and allow the shutters to slide easily through the slots 16 in the sashes.

From the foregoing description of and construction and operation of my new improved window, it will be obvious that I have provided a simple and efficient form of horizontally swinging sash, which is provided with a shutter and which parts are adapted when swung to open position, not to project beyond the sill and into the room. When the sash is swung open the same may be easily moved across the frame so that it will not be in the way, and when the sash is closed and it is only desired to open the shutter or blind, the same may be swung horizontally to open position and then slid transversely through a slot in the sash to a position which projects half from either side of the sash and will be disposed entirely within the frame 1. The ends of the sashes or shutters will not project into the room and be in the way such as is an ordinary objection to horizontal swinging sashes and shutters of this character.

I claim:

A device of the class described comprising a frame, a closure for said frame, vertical pivot pins projecting from the top and bottom of said frame adjacent its corners, horizontal rollers on opposite sides of said

pivot pins, and bearing pins carrying said rollers and extending laterally from said pivot pins in the plane of the closed position of the closure, said closure having longitudinal tracks at its upper and lower edges into which the free ends of said pivot pins project, said pivot pins allowing said closure to swing at right angles to the frame, whereby it may slide transversely therethrough, said 10 rollers engaging the edges of said closure

and being operable during both swinging and sliding of said closure.

In testimony whereof I have hereunto set my hand in the presence of two subscribing witnesses.

GIUSEPPE SINDONI.
